UNITED STATES PATENT OFFICE

2,549,160

SMALL TOOL STERILIZER

James Victor Bess, Leavenworth, Wash.

Application April 15, 1949, Serial No. 87,782

5 Claims. (Cl. 21—83)

1

My present invention relates to the general class of preserving and sterilizing apparatus forming portable cabinets, receptacles or kits of the closed chamber type and more specifically to an improved small tool sterilizer which while well adapted for various purposes and uses is especially designed for the tonsorial art in sterilizing razors, shears, and other tools or instruments employed by barbers, in accord with sanitary laws and regulations.

The invention is embodied in a portable cabinet having a closed chamber in which a receptacle containing formaldehyde or other sterilizing agent is confined, and a movable tray or drawer for supporting the tools or instruments is enclosed and sealed against escape of gas in both open and closed positions.

The sterilizer includes a minimum number of parts that may be manufactured with facility and low cost of production and the parts may be assembled with convenience to assure a cabinet that is simple in construction and operation, readily accessible for housing as well as for removal of the tools or instruments, durable, and sanitary.

The invention consists in certain novel features of construction and combinations and arrangements of parts as will hereinafter be described and more particularly pointed out in the appended claims.

In the accompanying drawings I have illustrated a complete example of a physical embodiment of the invention in which the parts are combined and arranged in accord with one mode I have devised for the practical application of the principles of the invention. It will however be understood that changes and alterations are contemplated and may be made in these exemplifying drawings and mechanical structures, within the scope of my claims, without departing from the principles of the invention.

Figure 1 is a vertical longitudinal sectional view partly in elevation, of a sterilizer in which the invention is embodied; and Figure 2 is a horizontal sectional view at line 2—2 of Fig. 1.

Figure 3 is a transverse vertical sectional view at line 3—3 of Fig. 1.

Figure 4 is an enlarged sectional view at line 4—4 of Fig. 3 showing part of the tray or drawer in open position.

Figure 5 is a perspective view showing the frame and hood around the opening of the cabinet; and

Figure 6 is a front elevation of the cabinet.

The portable cabinet of rectangular shape is

preferably made up with walls as 1 of glass and an open metallic frame 1a forming corner posts and horizontal bars, and the sterilizing chamber is equipped with a front hinged door 2 and knob 3 for access in supplying the sterilizing agent.

The interior space of the cabinet forms a closed sterilizing cabinet for the fumes or gas from the sterilizing agent, and the chamber is equipped with an interior reticulated or foraminous shelf 4 supported on brackets 5, and adapted to receive instruments or tools that are held in reserve or not frequently used.

The tools or instruments frequently used are contained in a drawer or tray located in the upper portion of the cabinet where the tools are readily accessible for use, and the side walls of the cabinet are provided with a pair of horizontal rails 6, 6, of angle irons that form tracks for a shallow drawer or slideable tray 7 having low sides 8 and a reticulated or foraminous bottom screen 9 that permits ready access of the sterilizing fumes to the instruments or tools on the tray.

The tray is provided with a front wall 10 to close a front opening in the cabinet, and the front wall may be equipped with a handle or hand pull 11 especially useful in holding the tray in open position, and the frame 12 around the cabinet opening is equipped with a sealing gasket 13 against which the front wall closes to seal the closed chamber.

The frame 12 forms part of a hood 14 located within the front opening, and this lining or hood at its inner diagonal or declining edge is provided with a sealing gasket 15 for coaction with the back or inner wall of the tray, and with spaced interior sealing gaskets 16, 16 for contact with the upper edges of the side walls 8 of the tray.

The front wall or front plate of the tray is of ample height and width to close and seal the opening of the cabinet, while the back wall 17 is lower or of lesser height to permit tilting of the tray when it is opened and the back wall is equipped with a sealing gasket 18 that contacts with the gasket 15 of the hood when the tray is pulled out to position of Fig. 4 to give ready access to the tools or instruments.

On the underside of its bottom the tray is also provided with a transversely arranged sealing gasket 19 that engages the inner face of the frame 12 when the tray is opened, and the sides 8 of the tray, near the back wall 17 are provided with sealing edge strips or gaskets 20 that contact with the sealing gaskets 16 of the hood when the tray

is opened. Thus means are provided for sealing the sterilizing chamber when the tray is closed, and means are provided for sealing the chamber when the tray is opened, to prevent escape of the fumes from the sterilizer.

For quick action in opening and closing the drawer or tray an interior lever arm 21 having a slot 22 at its upper end is engaged over a pin or fastener 23 mounted on and projecting from one of the sides of the tray, and the lever arm is rigid with a crankshaft or journal 24 mounted in a side wall of the cabinet. An exterior hand crank 25 with its knob or handle 26 is rigidly mounted on the crank shaft or rock shaft, and it will readily be apparent that a pull or swing of the crank handle will open the tray, while the tray may be closed by a push on the crank handle.

Having thus fully described my invention, what I claim as new and desire to secure by Letters Patent is:

1. In a small tool sterilizer of the closed chamber type, the combination with a cabinet having spaced side rails dividing the cabinet into upper and lower chambers, and the upper chamber having an access opening therein, and a sealing hood for the opening of the cabinet, of a tool-supporting tray slideable on the rails, a front plate and a back plate rigid with the tray, sealing means on said plates for alternate coaction with said hood, and means for sliding the tray through the opening.

2. The combination with a portable cabinet of the closed chamber type having a front opening and a sealing hood therein adjacent said opening, and spaced side rails forming an interior track, of a tool supporting tray slideable on the track, an exterior crank handle mounted in a wall of the cabinet, an interior lever arm rigid with the crank handle, a loose operative connection between the lever arm and the tray, and coacting means on the tray and the cabinet and hood for sealing the opening in the chamber.

3. The combination with a closed-chamber

cabinet having a front opening, and interior side rails, of a tool-supporting tray slideable on the rails, an exterior crank handle mounted in a wall of the cabinet, a slotted lever-arm within the cabinet and rigid with the crank handle, a pin on the tray coacting with the slotted lever arm, and coacting means on the cabinet and the tray for sealing the opening in the cabinet for the open and closed position.

4. In a portable sterilizer of the closed chamber type, the combination with spaced interior side rails, a sealing hood within a front opening of the chamber, and exterior and interior sealing gaskets on the hood, of a tray slideable on the rails and means for reciprocating the tray, sealing gaskets on the tray for coaction with the exterior sealing gasket of the hood, and a sealing gasket on the inner end of the tray for coaction with the interior sealing gasket of the hood.

5. In a portable sterilizer of the closed chamber type, the combination with a cabinet having interior side rails, a hood within a front opening of the cabinet and an exterior sealing gasket on the hood, and said hood having an inclined inner edge and a sealing gasket thereon, of a tray slideable on the rails and means for reciprocating the tray, said tray having a reticulated bottom portion, a front wall and a rear wall, a sealing gasket on the bottom of the tray for coaction with the open front of the cabinet, and a sealing gasket on the inner wall of the tray for coaction with the inclined inner edge of the hood.

JAMES VICTOR BESS.
